UNITED STATES PATENT OFFICE.

THEODORE NICOLAS CORESSY KORESSIOS, OF LONDON, ENGLAND.

AUXILIARY AIR-ADMISSION DEVICE.

1,238,691.

Specification of Letters Patent. Patented Aug. 28, 1917.

Application filed November 7, 1916. Serial No. 130,093.

To all whom it may concern:

Be it known that I, THEODORE NICOLAS CORESSY KORESSIOS, a subject of His Majesty the King of England, and resident of Old 5 Broad street, in the city of London, Kingdom of England, have invented certain new and useful Improvements in Auxiliary Air-Admission Devices for Internal-Combustion Engines, of which the following is a specification.

It is well known that even with the most up-to-date carbureters it is impossible to obtain in one operation, a perfect mixture of petrol with air, as a considerable quantity of 15 molecules of petrol remain in suspension in the mixture obtained, without being saturated with air, and instead of being transformed into an explosive gas they enter the engine cylinders and are simply burnt without the explosive effect.

In order to obtain a perfect mixture the operation of mixing must be repeated many times, viz., the mixture of petrol and air that is obtained in the carbureter passes into a 25 mixer and has a new quantity of air introduced thereinto, and the mixture obtained in the mixer passes into a third mixer in which a further addition of air is introduced, and so on until every petrol molecule is absolutely saturated. In practice these operations are limited to two carbureters and the induction pipe can be utilized as a mixer by opening a hole in its wall for the admission 30 of air.

The idea of saturating with air the free molecules of petrol by an introduction of air at the moment when these molecules, carried by the mixture, pass through the induction pipe has been long since adopted, and a 35 large number of additional air-inlet devices are on the market.

The mixing of air with free molecules of petrol in the mixer, (induction pipe), must be performed under absolutely the identical 45 conditions as the mixing of petrol and air in the carbureter. In the carbureter the air, as well as the petrol, is influenced by the direct pressure of the atmosphere, viz., under the same degree of pressure; for the mixer 50 also this law must be rigorously observed, viz., the degree of atmospheric pressure (or vacuum) on the mixture which contains the petrol molecules, and the degree of atmospheric pressure (or vacuum) on the air which is to be introduced, must be equal,

The mixture in motion in the induction pipe is subject to a variation of pressure (or vacuum) and this variation is regulated by the degree of vacuum produced by the aspiration of the engine pistons. In order then 60 to introduce into this mixture a quantity of air with the object to saturate the free molecules of petrol, it is desirable that this air be brought to the same degree of pressure (or vacuum) as that which effects the mixture 65 at the moment of the introduction. Beyond this, the air must be regulated according to the quantity, the speed, and the richness in petrol of the mixture passing through the induction pipe.

When the engine starts, or when it runs very slowly, the proportion of petrol must be much larger than when the engine is in full motion. In the first case the mixture obtained in the carbureter is suitable for the 70 purpose and the new admission of additional air must be completely suppressed, and only when the engine has obtained a certain speed may a further quantity of air be admitted, and this admission of air must be increased 75 in proportion to the increase of the speed of the engine, but this air must always be kept under the same variations of pressure that affects the mixture. The pressure decreases with the increase of the engine speed 80 and vice versa. The apparatus provided by the invention is conceived and constructed to fulfil the above conditions.

The apparatus is actuated in conjunction with the throttle valve of the carbureter and 85 saturates with air the free molecules of petrol existing in the explosion mixture obtained in the carbureter and not saturated by the first operation, by bringing the atmospheric pressure of the new quantity of air 90 required to the same pressure as that of the mixture moving through the induction pipe.

I will now describe my invention with reference to the accompanying drawings, in 95 which:—

Figure 1 is a partly sectional elevation of the preferred mechanism for controlling the air admission device in conjunction with the control of the carbureter.

Fig. 2 is a central vertical section of the 105 air admission device.

Fig. 3 is a transverse section of the mechanism shown in Fig. 1.

Fig. 4 is a horizontal section of the de- 110 vice shown in Fig. 2,

Fig. 5 is a detail view of the spring valve. Figs. 6, 7 and 8 are plans of the disks 15, 18 and 24, respectively.

Fig. 9 shows the lid of the air admission device forming a dial indicating the degrees of admission of air.

Figs. 10 and 11 are respectively, a cross section and a partly sectional elevation of a modified form of mechanism for operating 10 the air admission device.

Figs. 12 and 13 show front and side elevations of the apparatus fitted to the accelerator pedal on the dashboard of the car.

The various figures of the drawings illustrate 15 the parts of the apparatus in the positions they occupy when the air admission device is fully open.

The apparatus consists of two distinct parts, the air admission device, Figs. 2, 4, 20 5 to 9, and the controlling mechanism, Figs. 1, 3, 10 and 11. The construction and working of the apparatus is as follows:—

Referring particularly to Figs. 1 to 9, a cylindrical box 14, is divided into two compartments by a disk 15, bearing a slot 16 and a hole 17. On this disk 15 another disk 18 having a slot 19 fixed on a spindle 20 and bearing a toothed wheel 21, can turn freely. On the upper end of the spindle 20 a pointer 22 is fixed, and a spring 23 presses the disk 18 against the disk 15 to insure a perfect contact between them. The compartment above the disk 18 is divided by two disks 24, each of which is formed with two slots 25 covered with fine metal gauze. The box 14 is provided with a lid 26 within which a ring 27 fitted with a disk 28 having slots 29 covered with gauze, can turn with a certain amount of friction. The lid 26 and ring 27 are each formed with two slots 30, so that by turning said ring 27 within the lid 26 the slot of the ring comes over the slot of the lid and can operate as a register for regulating the admission of the air into the device. The upper surface of the lid 26 forms a dial divided into eight parts bearing the figures 4^a; 0, 1, 2, 3, 4 and 0^a.

The wheel 21 meshes with a toothed rack on bar 31 connected by a rod 32 to another 50 toothed rack or bar 33, which rod and racks are slidably mounted within a square tube 34. The rack 33 is in mesh with a sector arm or lever 35 the arcuate edge of which is formed by a number of teeth, and which arm pivots 55 on a spindle 36.

If desired and as illustrated in Figs. 10 and 11, the teeth on the sector arm and rack 33, can be replaced by a finger or lug 37 and a bar 38 formed with a slot 39 respectively. A second lever or arm 40 is provided which lever is formed with a number of tapped holes 41, into any one of which holes a headed and shouldered screw 42 can be screwed. This lever pivots on a spindle 43 65 on which a sleeve 44 is fitted and riveted

at 45, which sleeve is adapted to receive the end of the spindle 46 of the accelerator pedal.

A flat spring valve 47 bearing a wedge 48 is secured on the disk 18 in such manner that 70 when pressed down said spring completely covers and closes the slot 19 and when released leaves said slot completely open.

The compartment under the disk 15 forms an airtight box through the side walls of 75 which a nipple 49 is fitted. A connecting nut joins this nipple with one end of a flexible tube 50, the other end of which tube is connected with the induction pipe of the engine. 80

The apparatus is preferably fixed on the dashboard of the car, the spindle 46 of the accelerator pedal 51 being adapted to the sleeve 44 as indicated in Figs. 12 and 13.

The operations of the apparatus are as 85 follows:—

When the pedal 51 is depressed the lever 40 moves downward or from right to left when considering Figs. 1 and 11, and forces the sector arm or lever 35 to follow this movement by the medium of the screw 42 or the lug 37 and slot 39. The arm or lever 35 pulls the bars 33 or 38, 32 and 31 down and the bar 31 turns the wheel 21 clockwise and the disk 18 turns in the same 95 sense on the disk 15, so that by this movement the slots 30 coincide and the slot 19 registers with the slot 16 and opens the admission of air through the device to the engine. At this position the pointer 22 100 points to 4 (Fig. 3).

When the accelerator pedal 51 moves upward the reversed motion of all the above parts is performed, the slot 19 moves away from the slot 16, and by this the passage 105 of air is cut off.

All engines require a very rich gas in small quantities for starting, and many of them require a rich gas in very great quantities for picking up. In the first case the 110 opening of the accelerator must be made gradually without admitting any more air than that provided by the air throttle of the carburetor. In the second case the accelerator must be pushed to fully open position but admitting no more air than that admitted by the air throttle of the carburetor. 115

For the first case when the pointer 22 points to 0 the end *a* of the slot 19 shown in 120 Fig. 7 is at a distance of about an inch from the end *b* of the slot 16 shown in Fig. 6 of the drawings, so that no admission of air is made during the course of the pointer from 0 to 1. At the point 1 the end 125 *a* starts registering with the end *b* and admission increases gradually as the slot 19 moves over the slot 16 and until the pointer reaches the point 4. For the second case when the pointer 22 reaches the point 4 the 130

wedge 48 on the spring 47 is brought under a small fixed bar 52 and when the disk 18 is turned slightly more with the pointer on 0° the wedge engages under the bar and 5 presses down the spring which shuts the slot 19 and cuts off all admission of air.

Many cars when running down hill cut off every admission of gas. Should this be the case, the pedal of the accelerator is completely released so that the pointer is moved to 4° and consequently the end *c* of the slot 19 is brought over the hole 17 of the disk 15, thus establishing an admission of air for cooling the cylinders and for acting as a 15 brake.

In carburetors the length of the arc that the lever controlling the throttle describes in its motion from fully open position to fully 20 shut position, varies enormously from $\frac{1}{2}$ to 2½ inches and this movement is consequently repeated by the accelerator pedal. The apparatus provided by the invention, on the other hand, describes from fully open to fully shut always the same length of motion. It is therefore absolutely necessary 25 to establish a standard device in order to combine in every case, the variable lengths of motion made by the throttle control levers of various makes of carburetors to the constant length of motion of the apparatus. This is obtained by the combination and adjustment of the two levers 35 and 40 in the 30 casing 53. The sector arm or lever 35 always describes the same angular motion that 35 is, from 4° to 0°. The lever 40, being connected with the accelerator pedal 51 in the manner described, its angular motion must be equal to the two extreme positions of the carburetor throttle, from fully open to fully 40 shut, which motion varies according to the make of the carburetor. The combination of these two lengths of arc into one is obtained by increasing or decreasing the effective 45 length of the lever 40 between the center of the spindle 43 and the center of the screw 42 by placing this screw in the correct hole 41.

The regulation of the pressure of the air admitted to the pressure of the gases in the 50 induction pipe, is performed as follows:—

When the engine is working and the pointer 22 is on 0, no admission, a vacuum, produced by the pistons is established with- 55 in the induction pipe, in the flexible tube 50, and in the compartment under the disk 15. When the pointer indicates the opening, the air sucked in owing to the vacuum enters 60 by the slots 30 and passes through the gauzed slots 25 and 29 of the disks 24 and 28, and through the flexible tube 50 into the induction pipe. Owing to the arrangement of the slots and the presence of the gauze the air

is caused to travel in a sinuous path and its 65 passage is obstructed in such a way that when it is at the end of its course about to enter the induction pipe, its atmospheric pressure or degree of vacuum, is the same as the degree of vacuum of the gases in the induction pipe. The regulation of the quantity of air to be admitted is performed, according to the suction power of the engine by the registers 30.

The resistance to the free passage of the air through the air admission device can be increased by filling the spaces between the 75 disks 24 with metal or other clippings or filings, or by placing gauze inside the connecting nipples of the flexible tubing 50.

What I claim is:—

1. Auxiliary air admission apparatus for 80 internal combustion engines, comprising a device for the admission of air, means for controlling the throttle of the carburetor of the engine, a slotted lever operatively connected to said air admission device, a disk 85 having a toothed wheel in the air admission device, a lever formed with a plurality of tapped holes and operatively connected to said throttle control means, a screw slidably seated within the slot and engaging any one of the 90 tapped holes and operatively and adjustably connecting the two levers to one another, and connecting means engaged with the slotted lever and the toothed wheel.

2. Auxiliary air admission apparatus for 95 internal combustion engines, comprising a device for the admission of air, means for controlling the throttle of the carburetor of the engine, a lever formed with teeth, a rotatable disk in said air admission device and 100 provided with a toothed wheel, a toothed bar meshing with the teeth on the lever, a toothed bar meshing with the teeth of the wheel, means connecting the two toothed bars together, a lever operatively connected 105 to the throttle control means, and means operatively connecting the two levers together.

3. Auxiliary air admission apparatus for 110 internal combustion engines, comprising a device for the admission of air and including a lower fixed disk and an upper disk rotatable on said lower disk, a flat spring valve carried on said rotatable disk, a wedge member on said spring valve, a fixed bar adapted to coöperate with said wedge member, means for controlling the throttle of the carburetor of the engine, a lever operatively connected to said rotatable disk, a lever operatively connected to said throttle control means, and means for operatively 115 connecting the two levers together.

In testimony whereof I have hereunto subscribed my name.

THEODORE NICOLAS CORESSY KORESSIOS.
